US00D751763S

(12) United States Design Patent
Goodman et al.

(10) Patent No.: US D751,763 S
(45) Date of Patent: * Mar. 15, 2016

(54) STYLING CADDY

(71) Applicant: Spectrum Diversified Designs, Inc.,
Streetsboro, OH (US)

(72) Inventors: Sheldon H. Goodman, Solon, OH (US);
Phaysouk Xayoiphonh, Akron, OH
(US); Jennifer K. Case, Middleburg
Heights, OH (US)

(73) Assignee: Spectrum Diversified Designs, LLC,
Streetsboro, OH (US)

() Term: 14 Years

(21) Appl. No.: 29/495,464

(22) Filed: Jul. 1, 2014

(51) LOC (10) Cl. 28-03

(52) U.S. Cl.

USPC D28/73; D26/38; D6/513; D6/566
